UNITED STATES PATENT OFFICE

ALICE A. STROECKER, OF CHICAGO, ILLINOIS

DESIGN FOR A COMBINATION INCENSE BURNER AND LAMP

Application filed February 16, 1933. Serial No. 47,235. Term of patent 3½ years.

To all whom it may concern:

Be it known that I, ALICE A. STROECKER, a citizen of the United States, residing at Chicago, in the county of Cook and State of Illinois, have invented a new, original, and ornamental Design for a Combination Incense Burner and Lamp, of which the following is a specification, reference being had to the accompanying drawing, showing my new design, Fig. 1 being a frontal perspective view thereof, and Fig. 2 being a fragmental rear view on a reduced scale.

I claim:—

The ornamental design for a combination incense burner and lamp, as shown.

In testimony whereof I affix my signature.

ALICE A. STROECKER.
